United States Patent Office

Des. 197,582
Patented Feb. 25, 1964

197,582

BOTTLE

John B. Campbell, Paramus, N.J., assignor to The Procter & Gamble Company, Cincinnati, Ohio, a corporation of Ohio

Filed Mar. 11, 1963, Ser. No. 73,922

Term of patent 14 years

(Cl. D58—6)

Fig.1

Fig.2

Fig.3

FIG. 1 is a front elevational view of a bottle with a cap showing my new design.

FIG. 2 is a side elevational view of the same with the cap removed.

FIG. 3 is a top plan view of FIG. 2.

FIG. 4 is a bottom plan view of the same.

I claim:

The ornamental design for a bottle, as shown.
